(57) **CLAIM**

The ornamental design for a heat press, as shown and described.

DESCRIPTION

FIG. 1 is a front, left, top isometric view of the heat press; FIG. 2 is a front elevation view of the heat press; FIG. 3 is a rear elevation view of the heat press; FIG. 4 is a left side elevation view of the heat press; FIG. 5 is a right side elevation view of the heat press; FIG. 6 is a top plan view of the heat press; and, FIG. 7 is a bottom plan view of the heat press.

The broken lines immediately adjacent to the shaded areas depict the bounds of the claimed design, while all other broken lines are directed to portions of the heat press that form no part of the claimed design.

The "cricut" lettering and icon forming part of the disclosure is a registered trademark of Cricut Inc.
